ASSIGNORS TO JOHN I. PAULDING, INC., OF NEW BEDFORD, MASSACHUSETTS, A
CORPORATION OF MASSACHUSETTS.

CLAMP FOR ELECTRIC SOCKETS.

Application filed May 6, 1928. Serial No. 107,128.

This invention relates to a clamp for electric lamp sockets and is more particularly designed with reference to sockets made of porcelain and similar materials which are 5 easily fractured.

It is customary in electrical installations in toilet and bath rooms and other rooms and spaces finished in white or light colors to provide electrical fixtures of white or tinted 10 porcelain corresponding in color to the finish of the room or space. In such cases, the electric light sockets and similar parts comprise an exterior casing of porcelain adapted for holding in its interior a porcelain carrying 15 wire terminals. These fixtures generally comprise two parts, a cap band or similar part adapted to be permanently mounted on the conductor or wires and a shell or socket within which is arranged the porcelain terminal member. Various means have been devised and used heretofore for holding the 20 cap and shell members together. In some cases, these members have been provided at their engaging edges with ears adapted to 25 receive fastening screws but such means are hard to manipulate and the ears detract from the attractive appearance of the socket as a whole. In other cases, the two parts are fastened together by a long central screw passing 30 through the porcelain terminal member and threaded into the cap but this arrangement has the disadvantage of being awkward to manipulate and involving a certain loss of time and labor in assembling the 35 socket and frequent loss of the fastening screw.

The main object of our invention is the provision of a clamp so constructed that the shell and cap can be easily and expeditiously 40 locked together in a tight relation.

Another object of the invention is the provision of a clamp which may be permanently locked on one member to avoid any possibility of it or any of its parts being separated 45 therefrom and lost.

A further object of the invention is the provision of a clamp of such construction that by the manipulation of a single screw the two parts of the socket are drawn together in 50 a tight relation without any possibility of the porcelain being cracked or fractured.

A further object of the invention is the provision of a clamp which is attractive in

appearance and which does not detract from the appearance of the socket as a whole. 55

Other objects of the invention will be more specifically set forth and described hereafter.

Our invention contemplates a clamp comprising an outer member and an inner member held permanently together by a tightening member loosely mounted in the outer member and threaded through the inner member. The outer member is formed to clamp the two members of the electric socket together by engagement with flanges on the 60 outer faces thereof and the inner member has a turned end adapted to ride on one end of the outer member to secure a tight clamping action of the outer member. This construction is especially adapted for use on porcelain sockets because it draws the two parts of the socket into a tight engagement and prevents any fracturing of the porcelain. 65

In the drawings illustrating the preferred form of the invention, Figure 1 is a side elevation of a porcelain electric socket made in two parts which are clamped together by two clamps on opposite sides thereof constructed in accordance with our invention; Fig. 2 is a vertical sectional view of a portion of said 70 socket and of a clamp on an enlarged scale, the two parts of the socket being shown in separated relation and the clamp in open position; Fig. 3 is a view similar to Fig. 2 but showing the two parts of the socket locked 75 together by the clamp; Fig. 4 is a front elevation of that portion of the cap and shell in separated relation to which the clamp is applied; Fig. 5 is a view in perspective of the inner member of the clamp and Fig. 6 is a 80 similar view of the outer member of the clamp. 85

Referring to the drawings illustrating the preferred form of our invention, there is shown a clamp comprising an outer clamping member 10 and an inner clamping member 12 held together by a screw 14 which is threaded through the inner member 12 and headed over at 16. The screw passes loosely through a central opening 17 in the outer clamping member, the head 18 of the screw holding the outer clamping member against removal. The opening 17 in the central member is countersunk so that when the clamp is tightened the rounded head of the screw projects 100 105 beyond the outer face of the

clamp. At one end the outer member has a bent over end clamping portion 20 and the other end of the outer member is bent inwardly at 21 toward the inner member and then straightened out at 22. The inner member 12 is bent inwardly at 24 around the threaded hole receiving the screw and one end 26 is bent inwardly toward the outer member to engage the inner face of the oblique portion 21 of said member.

In the use of our invention, for locking two members of an electric fixture together, two clamps are employed on opposite sides of the fixture and preferably each member of the fixture should be provided with a flange at that end which engages the other member of the fixture to afford a grip for the clamping ends of our device.

To illustrate the method of use we have shown in the drawings, one form of a two part porcelain electric lamp socket to which the clamps may be applied. This socket comprises a cap member 30 of usual form provided with a flanged edge 32 and a shell member 34 also having a similar flange 36 at its upper adapted to engage the flanged edge 32 of the cap when the two members are in assembled relation (Fig. 1). Each of the socket members is provided with suitable recesses to receive the clamping members and to permit the clamp to be locked permanently on the socket member of the fixture. To accommodate the screw 14 connecting the two clamp members, each of the socket members is provided on each side with a semi-circular recess 40 which together form a circular opening when the two members are together. Said recesses are centrally located in the walls of the cap and socket the inner and outer wall faces adjacent the recesses being bevelled to receive the inwardly bent circular portions of the two clamping members. The flange 32 on the cap is also cut out at 44 to receive the obliquely bent clamping end 20 of the outer clamping member 10 and below the flange 36 the socket member has a rectangular through and through opening 46 through which passes the lower bent end of the member 10. The inner face of the wall of the socket is recessed longitudinally at 48 from the opening 46 to accommodate the end 22 of the outer clamping member.

The clamp may, if desired, be mounted permanently on the socket member 34 to guard against separation therefrom and so that it will be always accessible when required for clamping the socket onto the cap. By loosening the screw 14 the two clamping members may be sufficiently separated to permit the clamp to be mounted in the position shown in Fig. 2 with the outer clamping member having its bent lower end inserted through the hole 46 and its extreme end 22 in the recess 48 and the inner member having its bent end 26 project outwardly through said recess 46

and engaging the inner face of the bent portion 21 of the outer member. By tightening the screw 14 the two members may be drawn together sufficiently to prevent the clamp from being separated from the socket member 34. When the socket member is to be secured to the cap, the screw 14 is loosened sufficiently to allow the upper ends to be split apart as shown in Fig. 2 at which time the socket may be placed in position with its flange 36 in engagement with the flange 32 of the cap. The tightening of the screw 14 then draws the two members of the clamp together into the position shown in Fig. 3. After these two members are drawn together the end 26 of the inner clamping member rides on the oblique face of part 21 of the outer clamping member and forces it downwardly thereby drawing the two parts of the electric fixture tightly together.

It is to be observed that in the tightening of the clamp by manipulation of the screw 14, that no strain is placed upon the corner portions of either the cap or the socket and therefore all tendency to fracture the corner edges of these porcelain members is entirely eliminated. The two members of the electric fixture are drawn into close engagement by the cooperative action of the bent end 26 of the inner member pushing upwardly and the end 20 of the outer member pushing downwardly and as both of these parts have large bearing surfaces, there is no tendency to fracture the porcelain.

It is to be observed that our clamp is of very simple construction and can be made at a low cost of production; that it can be permanently locked on the socket member when the parts are shipped to avoid any loss of the clamps during the handling and lastly that the operation of the mounting of the socket on a cap involves nothing more than the manipulation of two screws in the two clamps on the opposite sides of the fixture. The clamps are preferably nickelized to harmonize with white porcelain and therefore add to rather than detract from the attractive appearance of the fixtures.

Although we have shown a clamp as applied to two part porcelain electric sockets, it is to be understood that it is capable of broad applications and may be used for connecting together two parts of various constructions of electric fixtures. Further, it is to be understood that our invention may be embodied in forms of construction other than that hereinbefore shown and described and we desire to claim it broadly except where specifically limited in the following claims.

What we claim is:

1. The combination with an electric fixture comprising two parts having flanged engaging ends and one of said parts being provided with an opening adjacent its flanged end, of a clamp for clamping said two parts

together, said clamp comprising an outer clamping member provided with oblique clamping ends for engaging the flanges of said two parts, one of said ends passing through the said opening in one of said parts and being adapted to engage the inner face of the wall of said part, an inner member engaging the inner faces of said parts and having one end turned to enter the said opening and to bear against the oblique portion of the end of the outer member within said opening and means connecting said outer and inner members to draw them together into clamping relation.

15 2. The combination with an electric fixture comprising two parts having flanged engaging ends and one of said parts being provided with an opening adjacent its flanged end, of a clamp for clamping said two parts together, said clamp comprising an outer clamping member provided with oblique clamping ends for engaging the flanges of said two parts, one of said ends passing through the said opening in one of said parts and being adapted to engage the inner face of the wall of said part, an inner member engaging the inner faces of said parts and having one end turned at right-angles to enter said opening and to bear against the oblique portion of the end of the outer member within said opening and a screw permanently connecting said outer and inner members to draw them together into clamping relation.

35 3. The combination with a two-part electric socket comprising a flanged cap and a shell of a clamp permanently mounted on the shell and comprising a screw headed at both ends, an outer clamping member loosely mounted on said screw and having one end bent over for encircling the flange on said cap and an inner clamping member threaded on said screw and having one end turned toward said outer clamping member for engaging the same and drawing said outer member downwardly into clamping action when said screw is manipulated.

45 4. The combination with a two-part electric socket, comprising a cap and a shell having flanged engaging ends and said shell having an opening adjacent its flange, of a clamp for clamping said two parts together, said clamp comprising an outer clamping member having one end turned obliquely inwardly through the said opening in said shell and then straightened to engage the inner face of said shell and having its other end bent inwardly to encircle the flange on the said cap, an inner member for engaging the inner faces of said cap and said shell and having one end turned to enter the said opening and to engage and ride on the oblique portion of said outer member therein and means for drawing said outer and inner members together to clamp said two socket parts together.

55 5. The combination with an electric fixture

comprising two parts having flanged engaging ends, one of said parts having an opening adjacent its flanged end, of a clamp comprising an outer clamping member having its two ends formed for encircling the flanges on said fixture parts, an inner member for engaging the inner walls of said fixture parts and having one end turned to enter said opening and to ride upon one end of said outer member and means for drawing said clamping members together to clamp said two fixture parts together.

6. The combination with an electric fixture comprising two parts having flanged engaging ends, one of said parts having an opening adjacent its flanged end, of a clamp comprising an outer clamping member having its two ends formed for encircling the flanges on said fixture parts, an inner member for engaging the inner walls of said fixture parts and having one end turned to enter said opening and to ride upon one end of said outer member and a screw for drawing said clamping members together to clamp said two fixture parts together.

7. The combination with an electric fixture comprising two parts having flanged engaging ends and one of said parts having an opening adjacent its flanged end of a clamp comprising an outer clamping member having its ends formed for encircling the flanges on said fixture parts, an inner member in engagement with the inner walls of said fixture parts and having one end turned to enter said opening in one of said parts and to ride on one end of said outer member and a screw for drawing said clamping members together to clamp said two fixture parts together.

8. The combination with an electric fixture comprising two parts having flanged engaging ends, one of said parts being provided with an opening adjacent its flanged end, of a clamp comprising an outer clamping member encircling the two engaging flanges of said fixture parts, one end of said outer member projecting into said opening in an oblique direction, an inner member engaging the inner walls of said fixture parts and having one end turned into said opening and engaging the oblique portion of the end of said outer member within said opening and a screw for drawing said clamping members together to cause said inner member to ride upon said outer member and to clamp said two fixture parts together.

9. The combination with an electric fixture comprising two parts having flanged engaging ends, one of said parts being provided with two openings adjacent its flanged end at opposite points, of a pair of clamps at opposite points on said fixture, each clamp comprising an outer clamping member encircling the two engaging flanges of said fixture parts, one end of said outer member projecting into one of said openings in an oblique

direction, an inner member engaging the inner walls of said fixture parts and having one end turned into said opening and engaging the oblique portion of the end of said outer member within said opening and a screw for drawing said clamp members together to cause said inner member to ride upon said outer member and to clamp said two fixture parts together.

10. The combination with an electric fixture comprising two parts having flanged engaging ends, one of said parts being provided with two openings adjacent its flanged end at opposite points, of a pair of oppositely dis-

posed clamps, each clamp comprising an outer 15 clamping member having its two ends formed for encircling the flanges on said fixture parts, an inner member for engaging the inner walls of said fixture parts and having one end turned to enter one of said openings 20 to ride upon one end of said outer member and means for drawing said clamping members together to clamp said two fixture parts together.

In witness whereof, we hereunto set our 25 hands this third day of May, 1926.

GUSTAF A. JOHNSON.
FRANK E. JOHNSON.
